UNITED STATES PATENT OFFICE.

WALTER WILLIAMS, OF DETROIT, MICHIGAN, ASSIGNOR TO PATRICK J. WALSH, OF DETROIT, MICHIGAN.

LIQUID-SOAP CONTAINER.

984,630.

Specification of Letters Patent. Patented Feb. 21, 1911.

Application filed November 8, 1909. Serial No. 526,711.

To all whom it may concern:

Be it known that I, WALTER WILLIAMS, a citizen of the United States, residing at Detroit, in the county of Wayne, State of Michigan, have invented certain new and useful Improvements in Liquid-Soap Containers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a liquid soap container, and consists in the construction and arrangement of parts hereinafter more fully set forth and pointed out particularly in the claims.

The object of the invention is to provide a simple and comparatively inexpensive container of the character described, wherein the arrangement is such as to enable a given quantity of the fluid contents of the container to be discharged from time to time as it may be required for use, provision being made for automatically stopping the flow of liquid from the container after the operation of the gravity valve in discharging a quantity of liquid therefrom.

The above object is attained by the mechanism illustrated in the accompanying drawings, in which:—

Figure 1 is a side elevation of a liquid soap container involving my invention, some of the parts being in section to show the construction and arrangement thereof. Fig. 2 is a horizontal section as on line 2—2 of Fig. 1. Fig. 3 is an elevation of the socket member which carries the bracket on which the container is supported.

Referring to the characters of reference 1 designates a globular body formed preferably of glass and adapted to contain liquid soap. Formed in the bottom or under side of said container is an opening 2 which is closed by a circular disk 3 having an annular flange 4 which embraces and is permanently secured to the neck 5 surrounding said discharge opening. The exterior of the disk 3 is threaded and screwed thereon is a depending housing 6 having a space 7 therein which forms a measuring chamber. Through the lower end of the housing 6 is a discharge opening 8 and surrounding said

opening within the housing is a valve seat 9 of soft metal, such as lead or analogous material.

Within the measuring chamber and normally lying upon the valve seat 9 is the ball-valve 10 having a straight stem 11 depending therefrom which projects through the discharge opening 8 and carries upon its lower end a knob 12. The ball-valve 10 is comparatively large and will be formed of material of high specific gravity so that its weight will normally be sufficient to hold it upon its seat and prevent the flow of liquid thereby, except at such times as the valve may be raised. In the disk 3 directly over the valve 10 is a beveled opening 13 through which fluid may pass from the container into the chamber 7, and which serves as a seat for the valve 10 when in the raised position. The ball-valve normally lying upon the seat 9, the chamber 7 will fill with fluid from the container so that when the valve is raised by an upward pressure upon the stem 11, the contents of said chamber will be discharged through the opening 8 onto the hand, which in operating the valve is pressed palm upward against the knob 12. As the valve is raised to permit the liquid to flow from the chamber 7, it is carried into contact with the seat surrounding the opening 13, thereby preventing a further flow of fluid from said chamber until released. By this arrangement there is discharged from said chamber each time the valve is lifted, only the fluid which has previously filled said chamber, thereby measuring the quantity which is discharged from the container at each operation. Upon releasing the valve, it falls to its seat, thereby preventing a further flow of liquid from the chamber 7 and allowing the chamber to refill through the opening 13. To prevent a possible sticking of the valve and to insure its quick return when released, a helical spring 14 is employed which is attached at 15 to the ball-valve at one end, and which at the other end bears against the under face of the disk 3 around the opening 13. This spring is slightly compressed when the ball is raised and the tension exerted thereby assists in returning the valve to its seat when released.

Surrounding the globular body of the container are the parallel beads 16 forming a channel therebetween. Lying in said chan-

2
nel and embracing one half of the globular body are the bracket arms 17 which serve to support the container in position. The arms 17 are in the form of curved forks and 5 extending horizontally from the junction thereof is a cylindrical stem 18. Secured to a fixed support is a conical socket member 19 having therein a socket which receives the stem 18 which is fitted therein to revolve 10 and to slide longitudinally. In the projecting outer end of the socket member are formed the opposed notches 20, and passing through the stem 18 is a transverse pin 21 whose projecting ends are adapted to normally lie in said notches to hold the stem 18 from turning and support the container 15 in operative position.

As it is necessary to invert the container for the purpose of refilling it, provision is 20 made for making a one half rotation of the stem 18 within the socket member by drawing it outwardly so as to free the ends of the pin 21 from the notches 20, when said stem may be rotated to place the housing 6 up- 25 permost, and it may be unscrewed and removed with the valve 10 to enable the container to be filled through the opening 13, after which said housing with the valve 30 therein is screwed into place and the container restored to its normal position. In order to hold the stem inwardly so that the ends of the pin 21 shall be yieldingly held within the notches 20, a coiled spring 22 is secured to the inner end of the stem 18 35 by a screw 23, or other suitable means, the other end of said spring being caused to engage the annular shoulder 24 within the socket member surrounding the socket in which said stem lies, whereby an inward pressure 40 is always exerted upon said stem to hold the ends of the pin in the notches 20. By pulling outwardly upon the container, the tension of the spring 22 may be overcome and the stem 18 drawn longitudinally 45 through the socket member such distance as to free the ends of the pin from the notches 20, as shown in Fig. 2, enabling the container to be inverted, when by releasing the outward strain upon the container, the tension 50 of the spring will be exerted to withdraw the stem into the socket member, causing the ends of the pin 21 to reenter the notches and lock the container in that position. Should it be desired to rigidly lock the stem 55 against movement in the socket member, the set-screw 25 threaded in the wall of said member may be screwed inwardly against said stem.

To enable the container to be removed 60 from the bracket arms 17, a semicircular strap 26 is employed which is hinged at its ends as shown at 27, to the ends of said arms.

By removing the pintle of one of said hinges, the strap 26 may be swung outwardly, as shown by dotted lines in Fig. 2, 65 to permit the container to be removed.

Having thus fully set forth my invention, what I claim as new and desire to secure by Letters Patent, is:—

1. A liquid soap container and dispenser 70 comprising a reservoir, a measuring chamber on the lower side of said reservoir, the upper wall of the measuring chamber having an induct opening connecting the reservoir with the interior of said chamber, the bottom of said chamber having a discharge opening therethrough, a weighted ball valve within said chamber having a stem of less area than said discharge opening protruding therethrough, a valve seat within the measuring chamber around the discharge opening, a valve seat in the under face of the upper wall of the chamber around the induct opening, said ball valve normally closing the discharge opening and adapted when 85 raised from its seat to lie in the upper valve seat and close the induct opening, and a spring through which the ball valve protrudes confined between the upper portion of said ball and the under face of the upper 90 wall of the measuring chamber around the upper valve seat.

2. A liquid soap container and dispenser comprising a reservoir having a bottom 95 therein with a flaring opening therethrough, a housing below said bottom forming a measuring chamber with which the opening in said bottom communicates, a discharge opening through said measuring chamber in vertical alinement with the opening in 100 said bottom, a valve seat around said discharge opening, a weighted ball valve in said chamber adapted to normally lie upon said seat, said valve having a depending stem which passes through said opening and through the medium of which said valve may be raised, the ball valve when lifted fitting into the flaring opening in the bottom of the reservoir to cut off the flow of liquid therethrough and permitting the liquid in 105 the chamber to flow out of said discharge opening, a helical spring attached to and embracing the upper portion of said ball and through which said ball protrudes, said spring engaging the under face of the bottom of the reservoir around the flaring opening in the bottom thereof.

In testimony whereof, I sign this specification in the presence of two witnesses.

WALTER WILLIAMS.
